LAMP HOUSING

John T. Armbruster, Niagara Falls, N. Y., assignor
to American Optical Company, Southbridge,
Mass., a voluntary association of Massachusetts

Application July 21, 1948, Serial No. 147,693

Term of patent 14 years

(Cl. D48—20)

To all whom it may concern:

Be it known that I, John T. Armbruster, a citizen of the United States of America, residing at Niagara Falls, in the county of Niagara and State of New York, have invented a new, original, and ornamental Design for a Lamp Housing, of which the following is a specification, reference being made to the accompanying drawings forming a part thereof.

In the drawing:

Figure 1 is a side elevational view of a lamp housing showing my new design;

Figure 2 is a top plan view thereof;

Figure 3 is a front elevational view; and
Figure 4 is a perspective view thereof.

The characteristic features of my new design reside in the portions shown in full lines in the drawing.

I claim:

The ornamental design for a lamp housing, substantially as shown and described.

JOHN T. ARMBRUSTER.
